REFRIGERATED FOOD MERCHANDISING CABINET

Robert B. Norris, Minneapolis, Minn., assignor to Schaefer, Inc., Minneapolis, Minn., a corporation of Minnesota

Filed Nov. 8, 1960, Ser. No. 62,779

Term of patent 14 years

(Cl. D80—11)

FIG. 1

FIG. 1 is a front perspective view taken from the top and left side of a refrigerated food merchandising cabinet showing my new design;

FIG. 2 is a front elevational view thereof, the rear being substantially plain;

FIG. 3 is a right side elevational view thereof; and

FIG. 4 is a top plan view thereof.

I claim:

The ornamental design for a refrigerated food merchandising cabinet, as shown and described.
